UNITED STATES PATENT OFFICE.

BARTON S. SNOW, OF BATAVIA, ILLINOIS, ASSIGNOR TO T. W. SNOW CONSTRUCTION COMPANY, OF CHICAGO, ILLINOIS, A CORPORATION OF ILLINOIS.

CRANE.

Application filed February 23, 1922. Serial No. 538,717.

To all whom it may concern:

Be it known that I, BARTON S. SNOW, a citizen of the United States, residing at Batavia, in the county of Kane and State 5 of Illinois, have invented a new and useful Improvement in Cranes, of which the following is a specification.

My invention relates to cranes for use in delivering liquid, preferably either water, 10 or fuel oil, to locomotives, this general type of apparatus being commonly located alongside of railway tracks for delivering the liquid to locomotives thereon.

Locomotive tenders are commonly provided with the filling openings thereof, whether the tender is to be used for receiving oil to be employed as the fuel for operating the locomotive, or water from which the steam is to be generated, at different 20 heights, there being no uniformity in this respect and, therefore, the filling spout of the crane must be adapted to be adjusted vertically to correspond with the various heights of tank-filler-openings. As the spouts 25 of the cranes are generally pivotally supported at the upper end of the column the extremities of the spouts are shifted horizontally, in the swinging movement of the spout, in moving through an arc, a considerable 30 distance in moving from one extreme position vertically to another extreme position to accommodate it to the various tank-filler openings. In fact, as cranes have hitherto been constructed, it is not possible to fill 35 all the different sized tenders, due to the relatively great movement of the extremity of the spout in a horizontal direction in the vertical swinging movement referred to. In this connection it is one of my objects 40 to provide a crane of such construction that for any given range of vertical movement of the extremity of the spout, the horizontal movement thereof will be materially reduced, as compared with constructions as 45 hitherto provided or in other words, the extremity of the spout will describe a curved path of a greater radius than in prior constructions, it being understood that for reasons of economy in construction, and 50 oftentimes by reason of the necessity of placing the crane closely adjacent to the track, as well as for other reasons, it is desirable that the crane be located as close

to the track as possible and still permit it to be adapted for the filling of tanks having filling openings extending at different heights. 55

Another feature of my invention relates more particularly to a crane provided for delivery of fuel oil, or any other liquid 60 which it is desired be conserved, and which is not drained away from the crane such as is the case in the use of water cranes, and which, it is desired, be retained in the crane against wastage; and in this connection it is one of my objects to provide means whereby the liquid remaining in the crane after completing the filling of a receptacle 65 from the crane, is retained therein.

Referring to the accompanying drawings: 70 Figure 1 shows, by a view in elevation, a crane for use in delivering liquid, such as fuel oil, and the supply of which is to be conserved, the spout portion of the crane being shown by full lines in the normal 75 raised position occupied by it when not in use except that the column on which it is supported would be swung upon its axis throughout one quarter of a revolution from the position shown in this figure, to cause 80 the spout to substantially parallel the track (not shown), alongside of which the crane is located, and by dotted lines one of the positions occupied by the spout when in tank filling position. Figure 1^a is a longitudinal section through the valve-equipped 85 spout, the section being taken at the line 1^a on Fig. 2 and viewed in the direction of the arrow. Figure 2 is an enlarged section taken at the line 2—2 on Fig. 1 and viewed 90 in the direction of the arrows. Figure 3 is an enlarged broken section taken at the line 3—3 on Fig. 1 and viewed in the direction of the arrows; and Fig. 4, a modification of the construction shown in the 95 preceding figures.

Referring to the construction shown in Figs. 1, 2 and 3, the crane comprises an upright, hollow, column 5 shown as formed of three aligning, end-to-end fittings, sections 6, 7 and 8, this column being rotatably supported at its lower end in the bearing portion 9 of the upwardly extending tubular portion 10 of an elbow 11 suitably supported, in the arrangement shown, in a pit 105 12, the elbow 11 being connected with a pipe

13, valved at 14, and extending from the supply of liquid under pressure, as for example, oil, to be delivered by the spout. The coupling 11 is also shown as connected 5 with the chamber represented at 15 and commonly provided for the purpose of preventing hammering action in the closing of the valve controlling the flow of liquid through the crane. The column 5 is shown 10 as surrounded, at the ground line, by a casing 16, and the section 7 of the column is shown as provided with a collar 17, secured thereto as by a set screw 18 and equipped with an operating lever 19 shown as pivotally connected therewith at 20, and by means of which column 5 may be rotated as desired on the bearing support 10.

The crane also comprises a laterally extending spout, or pipe, section 21 located at 20 the upper end of the column 5 and having hollow ball and socket connection therewith, adapting the spout section 21 to be moved vertically on the column 5 at the pivotal connection thus provided. The ball and 25 socket connection referred to is shown as provided at the upper end of the column 5 with its center co-incident with the longitudinal axis of this column, and in the particular construction shown comprises the 30 following described parts. The socket portion of the joint and represented generally at 22, comprises the lower, hollow member 23 presenting an internal, segmental, spherical surface 24, the member 23 opening 35 at its neck portion 25 into the upper end of the section 6 at the column 5, the section 6 and the member 23 being flanged as represented at 26 and 27 by which portions they are secured together as by bolts 28. The 40 socket portion 22 also comprises a ring shaped member 29 superposing the section 23 and secured thereto as by the bolts 30, the ring member 29 being shown as provided with screws 31 having threaded engagement 45 therewith and screwing down against a packing ring 29^a confined between the members 23 and 29 and bearing against the hereinafter described ball portion to the joint. The ball portion of the joint is represented 50 at 32, this member being of hollow form open at its lower end its exterior surface being of a segmental, spherical contour. The ball member 32 is located within the socket member hereinbefore described and 55 while confined therein against vertical displacement, is adapted to rock in the socket portion. The member 32 is formed with an upwardly extending hollow neck portion 33 opening at its lower end into the interior 60 of the ball portion of the member 32 and at its upper end into a depending tubular portion 34 provided as a part of the spout 21 and communicating with the interior of the latter, the members 32 and 34 being provided 65 with flanges 35 and 36 respectively, at which

these parts are secured together as by bolts 37.

Means are provided for preventing swinging movement of the spout 21 on the column 5, except in a vertical direction, these means 70 comprising bracket members 38 secured to the section 32, at opposite sides of the ball and socket joint, by the bolts 37, these brackets being provided at their depending portions with pins 39 arranged in line with the point about which the ball section 32 rotates in the socket member and extending into sockets 40 contained in the socket-section 23.

The crane also comprises means for normally, yieldingly holding the spout section 21 in the raised position shown in full lines in Fig. 1, these means, shown as of a construction commonly employed for this same general purpose in water cranes, comprising a coiled spring 41 connected at its lower end with a bolt 42 interlockingly engaging with a lug 43 on the column 5, and connected at its upper end, through the medium of the rod 44, with the rear end of the 85 spout section 21, the spring being shown as encased in a cylinder represented at 45.

In the particular construction shown the valve mechanism for controlling the discharge of liquid through the spout 21, is located wholly within the latter except for the actuating hand-wheel hereinafter referred to, this valve mechanism, which may be of any desirable construction, the particular construction shown being that disclosed in my pending application for U. S. Patent, Serial No. 538,718, filed February 23, 1922, being represented at 46 and controllable through the medium of the hand-wheel 47 above mentioned, journaled on the spout 21 adjacent its outlet, any suitable connections being provided between the valve 46 and the hand-wheel 47 for effecting the control of the valve through the medium of this hand-wheel, the connections being located in the particular arrangement shown, within the spout section 21.

The particular crane shown being provided for use with liquid, the supply of which is to be conserved to avoid waste, and spilling thereof from the spout upon the road-bed, is to be avoided, I preferably provide the discharge end of the spout 21 as a separate, elbow section represented at 48 swivelled at one end to the body portion of the spout beyond the hand-wheel 47, to adapt the discharge end 49 of the section 48 to be moved into a position in which it extends upwardly as shown in full lines in Fig. 1, or extends downwardly as by dotted lines in this figure. In the use of the crane for discharging liquid therefrom into a receptacle, the section 48 would be turned to its connection with the body portion of the spout 21, to the depending position shown

by dotted lines in Fig. 1, and at the conclusion of the filling operation, the operator would rotate the section 48 on the body portion of the spout to cause its discharge end 49 to extend upwardly, and prevent the spilling of the liquid from the spout, this feature of my construction also preventing objectionable spilling of the liquid from the spout in the swinging of the latter from the upwardly extending position shown in full lines in Fig. 1, to the downwardly inclined position shown by dotted lines in this figure, in the adjusting of the spout to a filling opening.

15 As hereinbefore stated, the spout section 21 and the column 5 are so connected together that they rotate as a unit about a vertical axis, so that the operator, following the completion of the filling operation, 20 and in swinging the spout section 21 to a position in which it extends out of the path of trains running on the track adjacent the crane, effects a turning of the column 5 on the bearing support 9, and to releasably 25 maintain the column against rotation, I provide the lever 19, which may also serve as a means for turning the column, which cooperates with a pair of lugs 50 spaced apart and extending laterally from the member 16 30 and into which space the operator positions the lever 19 for holding the column against rotation.

The construction shown in Figure 1 is particularly advantageous where the column 5 is formed of cast metal pipe sections, the section 7 being shown as provided with a groove 51 in its periphery to cause the column to be weakened at this point to a sufficient degree to insure the fracturing of the column at the section 7, should the crane be subjected to stresses sufficient to impair it.

The construction shown in Fig. 4 is the same as that shown in the preceding figures, except that the column represented at 5^a in this case is shown as formed of a single pipe section which may be, and preferably is, of steel, the lower end of this column being rigidly connected, against rotation, with the pipe 50 through which the liquid is supplied to the crane, this pipe being represented at 13^a. In this particular construction the ball and socket connection between the spout 21 and the column 5^a is the same as that described in the preceding figures except that the studs 39 are omitted, whereby the spout is free to be moved on the column 5^a, except as yieldingly restrained by the spring 41, in all directions, except that it cannot rock on an axis extending lengthwise of the spout, as the brackets 38, in co-operating with the annular peripheral surfaces of the socket sections 23 and 29 prevent such rocking movement.

65 It will be noted that in both of the con-

structions shown the center of the ball and socket connection between the spout and the column is in vertical alignment with the longitudinal axis of the column and thus, the arc described by the discharge end of the spout in swinging in a vertical plane, is of relatively great radius, as compared with those structures wherein the pivotal connection of the spout with the column is forward of the vertical axis of the column, and the crane is thereby adapted for use in filling tenders the heights at which the filling openings therein extend above the ground vary within wide ranges.

It will also be noted that by locating the connections between the valve-actuating element, the hand-wheel 47 in the construction shown, and the valve-pipes, these parts are not subject to the weather and thus freezing of the same, impairing their operation, is avoided.

While I have illustrated and described certain forms in which my invention may be provided, I do not wish to be understood as intending to limit my invention thereto, as the same may be variously modified and altered without departing from the spirit of my invention, and the invention may be provided in various other forms.

What I claim as new, and desire to secure by Letters Patent, is:

1. A crane comprising an upwardly-extending hollow column, and a pipe section extending laterally from said column at the upper end of the latter and swingable thereon in a substantially vertical plane, the axis about which said pipe section swings being in substantially vertical alignment with the vertical longitudinal axis of said column, and valve mechanism located adjacent the upper end of said column, the outlet end of said pipe section being formed of a rotatably-supported portion having a downwardly-directed outlet opening adapting said portion to be swung into and out of a position in which said outlet opening extends downwardly.

2. A crane having an upright hollow column rotatable about a substantially vertical axis, and a pipe section extending laterally from said column at the upper end of the latter, and a hollow substantially vertically disposed ball-and-socket connection between said pipe section and said column, and means preventing rotary movement of said pipe section on said column on an axis extending lengthwise of said pipe section.

3. A crane having an upright hollow column rotatable about a substantially vertical axis, a pipe section extending laterally from said column at the upper end of the latter, a hollow substantially vertically disposed ball-and-socket connection between said pipe section and said column with the center of said connection in substantially vertical

alignment with the longitudinal axis of said column, and means preventing rotary movement of said pipe section on said column on an axis extending lengthwise of said pipe section.

4. A crane comprising an upwardly-extending hollow column, and a pipe section extending laterally from said column at the upper end of the latter with a joint between said pipe section and column adapting said pipe section to swing on said column, and a valve located in said pipe section in substantial vertical alignment with said joint.

5. A crane having an upright hollow column rotatable about a substantially vertical axis, and a pipe section extending laterally from said column at the upper end of the latter, and a hollow substantially vertically disposed ball-and-socket connection between said pipe section and said column, and means preventing rotary movement of said pipe section on said column on an axis extending lengthwise of said pipe section, and in a horizontal plane.

25 6. A crane having an upright hollow column rotatable about a substantially vertical axis, a pipe section extending laterally from said column at the upper end of the latter, a hollow substantially vertically disposed ball-and-socket connection between said pipe section and said column with the center of said connection in substantially vertical alignment with the longitudinal axis of said column, and means preventing rotary movement of said pipe section on said column on an axis extending lengthwise of said pipe section, and in a horizontal plane.

7. A crane comprising an upwardly-extending hollow column, and a pipe section extending laterally from said column at the upper end of the latter, a hollow substantially vertical disposed ball-and-socket connection between said pipe section and said column, and a pair of spaced-apart lugs carried by said pipe section and located at opposite sides of, and cooperating with, that

portion of the ball-and-socket which is carried by said column.

8. A crane comprising an upwardly-extending hollow column, and a pipe section extending laterally from said column at the upper end of the latter, a hollow substantially vertically disposed ball-and-socket connection between said pipe section and said column, the ball portion of said connection being on said pipe section and the socket portion on said column, and a pair of spaced-apart lugs carried by said pipe section and located at opposite sides of, and cooperating with, the socket portion on said column.

9. A crane comprising an upwardly-extending hollow column, and a pipe section extending laterally from said column at the upper end of the latter, a hollow substantially vertically disposed ball-and-socket connection between said pipe section and said column, and a pair of spaced-apart lugs carried by said pipe section, said lugs having portions which extend at opposite sides of, and engage with, that portion of the ball-and-socket which is carried by said column and prevents said pipe section from rotating on its longitudinal axis.

10. A crane comprising an upwardly-extending hollow column, and a pipe section extending laterally from said column at the upper end of the latter and swingable thereon in a substantially vertical plane, the axis about which said pipe section swings being in substantially vertical alignment with the vertical longitudinal axis of said column, and valve mechanism located adjacent the upper end of said column in substantially vertical alignment with said axis, the outlet end of said pipe section being formed of a rotatably-supported portion having a downwardly-directed outlet opening adapting said portion to be swung into and out of a position in which said outlet opening extends downwardly.

BARTON S. SNOW.
